UNITED STATES PATENT OFFICE

ULYSSES G. HARING, OF WASHINGTON, DISTRICT OF COLUMBIA, ASSIGNOR OF ONE-FOURTH TO GUSTAV ESCHER, OF WASHINGTON, DISTRICT OF COLUMBIA, AND ONE-FIFTH TO HERMAN R. KUEHNER, OF LAUREL SPRINGS, NEW JERSEY

WATER CLOSET

Application filed November 6, 1930. Serial No. 493,867.

My invention relates to new and useful improvements in water closets, and has for an object to provide a combined tank and bowl wherein there is a water chamber extending completely about the bowl, so that the tank may be made smaller than would otherwise be the case.

Still another object of the invention is to provide a water closet comprising a bowl and an integral tank at the rear thereof, and wherein a relatively large water chamber extends from the tank around the wall of the bowl, so that the necessary six gallons of water may be held but, at the same time, the tank may be relatively small and occupy but little additional space to the rear of the bowl.

Still another object of the invention is to provide a water closet wherein the bowl has a peripheral rim which is provided with two small passageways, one for air and the other for water, and to provide mechanism whereby when the seat is occupied a small amount of water will flow from the peripheral passageway in the rim down the sides of the central well or central portion of the bowl to wash the same and, at the same time, a vacuum will be caused in the second passageway in the rim to draw out the air or odors from the bowl, which will then be passed on out through a waste pipe.

Still another object of the invention is to provide a water closet comprising a combined tank and bowl wherein the water will surround the bowl to thus lessen the size of the tank and, at the same time, to also provide means for slightly washing the bowl during the time that the seat is depressed and to automatically cause the air to be drawn from the bowl by a vacuum caused by a small jet of water extending across a passageway leading to the rim of the bowl.

Still another object of the invention is to provide a closet with a combined integral tank wherein there is no danger of flooding should the bowl become clogged up, as the normal height of the water in the tank and around the bowl is below the upper surface of the bowl and the main supply will cut off when the normal water level height is reached.

Still another object of the invention is to

provide a water closet wherein the tank might be said to extend completely around the bowl and thus occupy a minimum space and to provide means whereby should the water fail to cut off, it will pass out through an overflow and down through the gooseneck of the bowl and thus prevent any flooding on the floor.

Still another object of the invention is to provide a water closet comprising a bowl and integral tank that will occupy but little space and, at the same time, may be easily and conveniently cast.

Still another object of the invention is to provide a water closet wherein the ordinary flushing means are used but with the addition of means for continuously washing out the bowl while the same is being used and, at the same time, to automatically vent the bowl.

With these and other objects in view, the invention consists in certain new and novel arrangements and combination of parts, as will be hereinafter more fully described and pointed out in the claims.

Referring now to the several views showing a preferred embodiment,

Fig. 1 is a top plan view of the improved water closet, parts being broken away for the sake of clearness of illustration;

Fig. 2 is a sectional view taken on the line 2—2 of Fig. 1, looking in the direction of the arrows, parts being left out of the tank for the sake of clearness of illustration;

Fig. 3 is a sectional view taken on the line 3—3 of Fig. 1 and looking in the direction of the arrows;

Fig. 4 is a vertical sectional view taken on the line 4—4 of Fig. 2, looking in the direction of the arrows;

Fig. 5 is an enlarged detail fragmentary section taken on the line 5—5 of Fig. 1.

Referring now more particularly to the several views and first describing the bowl and tank rather than the mechanism contained therein, there will be seen the improved water closet, which comprises the bowl 1 and the integrally formed tank 2. In Fig. 1, it may be seen that this bowl is substantially circular in outline but having its sides continued, as at 3, and widened out slightly, as at 4, to merge with the flat sides 5 of the tank

2. The rear portion of the tank, therefore, is substantially rectangular, and it will be seen that it is of relatively narrow width. This is possible, because around the well or central 5 chamber or depression 6, there is the water chamber 7, so that the water from the tank will extend in this chamber completely around the said well.

There is the usual trap 8, and the wall 9 of the well extends down into the same to form a seal. There is also the usual gooseneck passageway 10, so that the water may pass upwardly and then downwardly through the same and out through the main discharge 11.

15 As also may be seen in Fig. 2, there is the main outlet 12 from the tank 2, which registers with the passageway 13 beneath the tank, which passageway, of course, extends into the trap of the well, so that when the closet is 20 flushed, the water will pass down into the trap and the usual siphonic action will take place.

By providing the water chamber 7 about 25 the well, the tank 2 may be reduced in size, as it is only necessary to hold six gallons of water to flush a water closet and, as will be seen, this water chamber 7 really forms part 30 of the tank 2. To the rear of the tank may be built the small overflow passageway 14, which registers with the passageway 13, so 35 that should the main valve break, the water, after reaching the top of the tank, will overflow through this passageway and out through the closet bowl.

35 Also formed in the tank, as may be seen in dotted lines in Fig. 1 and in section in Fig. 3, there is a small compartment 15 with an opening 16 near its top and the opening 17 at its bottom that registers with the tank. 40 There is also a vent pipe 18 connected therewith, as it is in front of this compartment that there is a vacuum formed to draw off the odors and the air from the bowl, as will be later described.

45 The top of the tank may have a cover 19 which, in this instance, is shown as triangularly-shaped, which gives a pleasing appearance to the closet.

Now referring to an important part of the 50 invention, there will be seen an integral peripheral rim 20 extending around the well of the bowl, substantially circular in outline and divided by a peripherally extending inner wall 21, so that there are really two passageways 22 and 23 formed. The passageway 23 is for drawing out the air from about the bowl and there are a plurality of small openings 24 around its lower edge. In the 55 same way, there are a plurality of small holes 25 in the passageway 22, so that when water is allowed to flow in this passageway, it will, in turn, run down from the rim and wash or lubricate the well. The connections and means for doing this will be shortly described.

60 The combined bowl and tank may be cast

in the one piece and may be cored in the base, as shown, to lighten the same, no difficulties being presented in casting over the ordinary form of closet.

Having thus described the bowl, the mechanism for causing the air and washing passageways to function, as well as the flushing arrangement, will now be described.

There is the main inlet water supply 26 (see Fig. 3) with a cut-off valve 27 at its top, the float 28 being connected to the rod 29 that extends to the valve 27. Any form of cut-off valve and float may be utilized and I have simply shown one of the standard makes.

There is also shown the ordinary discharge 80 valve 30 with its stem 31, which is operated by the lever 32 when the small handle 33 is operated. This, too, is of standard construction.

Now, to vent and wash this specially constructed bowl, I employ generally a mechanism for creating a small vacuum, as illustrated in the patent granted to Edgar E. Sutter, Ralph Haring, and me on April 27, 1926, No. 1,582,748.

90 Mounted near the front wall of the tank 2 is a small pipe 34 with a nozzle 35 thereon that is directly opposite the openings 16 in the compartment 15 but spaced a slight way therefrom. The pipe 34 extends diagonally and is connected to a valve 35', which may be clearly seen in Fig. 2. This valve has a ball 36 therein, which is operated by the stem 37, which is spring-pressed, as at 38. The stem has a small nipple or top 39 thereon, which bears against the under side of the seat 40 and, as shown in Fig. 2, the valve is normally held in its closed position.

95 Also connected to this valve 35' is the inlet pipe 41 that extends rearwardly and is connected to the main inlet 26. Thus, when the seat 40 is depressed and the valve is actuated, water will flow from the main inlet pipe 26 in through this by-pass 41, and the valve 35' now being open the water will pass upwardly and through the pipe 34 and out the nozzle 35 100 to spray into the small compartment 15 in the tank.

105 It is to be mentioned here also that there is a small T 42 that leads from the pipe 34 into the peripheral passageway 22 of the rim 110 20, so that not only is there a jet of water shooting into the compartment 15, the purpose of which will be shortly mentioned, but there is also a stream of water being shot into this peripheral passageway 22, which will run 115 down through the openings 25 and lubricate or wash the well of the bowl.

120 Referring for the moment to Figs. 1 and 5, there will be seen a pipe or passageway 43 that has its opening, as at 44', right opposite the nozzle 35 and this passageway 43 extends across the outer peripheral passageway 22 and into the passageway 23 at the point 44. This passageway 43 is above the normal water line 45 in the tank 2, so that there is no danger 125 130

of the water in the tank running back through the passageway 43 into the peripheral passageway 23.

Thus, it will be seen that when the seat 40 is depressed, the valve 35' is opened and not only will water be passed into the peripheral passageway 22 and flow down into the well of the bowl, but also a jet of water will be blown into the compartment 15 and cause a vacuum directly in front of the opening 44', which is at one end of the passageway 43, and will cause this vacuum to draw the air from the central well up through the openings 24 and out through the peripheral passageway 23 to thus ventilate the closet. The water, in turn, from the spray will fall back into the tank and the gases or air will pass from the small chamber 15 up and out the vent pipe 18, which is shown as a swinging pipe, so that it may be conveniently connected to the ordinary vent pipe connected to all closets.

From the foregoing, it will be seen that I have constructed a water closet wherein the tank and bowl are integral parts and wherein the tank extends around the bowl to thus provide a maximum capacity of the bowl and a minimum-sized tank. It will also be seen that I have formed a peripheral rim in which there are two peripheral passageways, so that all the time the seat is being depressed, a small amount of water will trickle down the sides of the bowl to wash the same and, at the same time, there is automatically created a vacuum in the rim to draw off the air and odors from the bowl.

The flushing of the bowl is done in the ordinary way and all of the water in the tank and about the bowl will drain into the trap when the closet is flushed.

Lastly, it will be seen that even should the trap become stopped up, the water will not overflow onto the floor, as the ball valve will operate when the tank is filled and the water level is below the top of the rim of the bowl.

I have found in actual use that the water used to create the vacuum and lubricate the bowl will not be over a gallon in twenty minutes, so that although the desired functions are performed as outlined, the amount of water utilized is very small.

It will be understood that other forms of valves might be used than those shown without in any way departing from the spirit and scope of the invention.

Having thus described my invention, what I claim as new and desire to secure by Letters Patent is:

1. A water closet comprising a bowl and an integral tank formed at the rear thereof and slightly wider than said bowl and communicating with a water chamber completely surrounding the well of the bowl, a hinged seat over the bowl, a trap beneath said well and water chamber provided with an outlet, an overflow communicating passageway between said trap and the upper portion of the tank below the upper edge of the bowl, a flush valve in the bottom of the tank communicating with said passageway to the trap, a peripheral rim about the well of the bowl provided with two non-communicating passageways, said passageways provided with small outlets to the well of the bowl, one of said passageways adapted to liberate water around the well of the bowl to wash the same, the other of said passageways adapted to withdraw the air from within the bowl, and a seat-operated valve adapted to liberate water to said water passageway and simultaneously effect a suction on the other passageway for withdrawing air from the bowl therethrough.

2. A water closet comprising a bowl and a tank formed therewith, a communicating water passageway extending around the well of the bowl and into said tank, a hinged seat over the bowl, a trap beneath the well and an outlet from the tank into said trap, a peripheral overhanging rim on the well of the bowl, said peripheral rim divided into two non-communicating perforated passageways, means for liberating water into one of said passageways to lubricate the bowl, means for drawing air through the other of said passageways to thereby vent the bowl, and means for simultaneously operating said water liberating means and air drawing means by depressing the seat.

3. A water closet comprising a bowl, a peripheral rim about the bowl and overhanging the well of the bowl, said peripheral rim provided with two perforated non-communicating passageways, a seat, means operated by the depression of the seat for flowing water through one of said passageways for washing the walls of the bowl and for drawing air from the bowl through the perforations of the other of said passageways.

4. A water closet comprising a combined tank and bowl, a trap beneath the well of the bowl, means for flushing the trap from said tank, a seat connected with said bowl and a valve operated by said seat, a peripheral rim having two distinct passageways therein, an inlet from the valve into one of said passageways to supply water thereto for washing the walls of the bowl when the seat is depressed to open said valve, a water jet also controlled by the valve, a passageway extending from near said jet to the other of said peripheral passageways in the rim whereby an opening of said valve will cause a vacuum in said rim to vent the bowl.

5. A water closet comprising a combined tank, bowl and trap, means for flushing the trap with water from the tank, an overhanging peripheral rim in said bowl provided with two perforated non-communicating passageways, a seat on said bowl, means in

the tank for forming a vacuum when said seat is depressed, said means connected to one passageway in the peripheral rim, and means for directing water into the other of 5 said passageways to thereby wash the walls of the bowl when the seat is depressed.

6. A water closet including a bowl and an integral tank, a communicating water chamber from the tank around the well of the 10 bowl, a trap below said tank and chamber, overflow and flushing communications between the tank and said trap, an overhanging peripheral rim on the upper edge of the bowl extending above the normal level of the water 15 in said tank and chamber and the top of said overflow and provided with two perforated non-communicating passageways, an inlet for one of said passageways and the inlet opening into the tank and above the 20 normal water level line of the tank, and means operable to draw air through said opening for ventilating the bowl and simultaneously supplying water to the other passageway to wash the walls of the bowl.

25 7. A water closet comprising an integral tank and bowl with the tank extending around the well of the bowl, a seat over the bowl, a passageway leading from the tank into the bottom of the well of the bowl for flushing the same, means operable for effecting said flushing, auxiliary means around the top of the bowl for permitting water to flow down and wash the walls of the bowl, a further passageway around the rim of the 30 bowl for ventilating the same, means operable by the seat for effecting the flow of said wash water into the bowl and simultaneously producing a vacuum operating in conjunction with said ventilating passageway.

In testimony whereof I affix my signature.
ULYSSES G. HARING.
